UNITED STATES PATENT OFFICE.

ADOLF SCHMIDT, OF TEGEL, NEAR BERLIN, GERMANY.

APPARATUS FOR DISINTEGRATING SEEDS.

Application filed November 17, 1921. Serial No. 516,003.

To all whom it may concern:

Be it known that I, ADOLF SCHMIDT, a citizen of the Free State of Prussia, in the German Republic, residing at Tegel, 5 near Berlin, Germany, have invented Improvements in Apparatus for Disintegrating Seeds (for which I have filed applications in Germany Sept. 30, 1920, and January 14, 1921); and I do hereby declare the 10 following to be a full, clear, and exact description of the same.

This invention relates to an improved apparatus or device for disintegrating or rough grinding corn, beans, peas and other 15 cereals comprising three grooved working members whereof two are stationary and the third one is disposed to reciprocate between the said two stationary members.

Generally speaking disintegrators of the 20 above kind are old. It, therefore, is to be understood that the invention does not reside in the general arrangement of the working members as above stated, but rather consists in a particular construction and arrangement of said members for the purpose 25 of improving the efficiency of the apparatus.

According to this invention the three members of the grinding element consist each of a preferably rectangular plate vertically positioned in a casing of appropriate 30 construction and provided with vertical parallel grooves extending across the full width of the plate from top to bottom. The two lateral plates have grooves of the 35 said kind on their inner faces only whereas the third or intermediate plate is provided with grooves on both sides. It goes without saying that vertical parallel grooves involve corresponding teeth or cutting ribs 40 constituted by the edges of said grooves and that, in case of combining a plurality of such elements to form a larger apparatus or machine, all of the parallel, vertical grinding plates may be provided with 45 grooves on both sides with the exception of the two extreme plates which are grooved on their inner sides only.

In distinction from the prior art the 50 grooves are, according to this invention, of gradually or stepwise decreasing width so that the upper parts of the grooves are broadest and the width diminishes towards the bottom preferably the lowest and nar-

rowest step of the grooves may be divided to produce at the bottom thereof a plurality 55 of divisional grooves of a still less diameter.

As regards the shape of the grooves a semicircular cross-section is to be preferred so that at each reciprocation of the intervening or movable plates the grooves thereof which are brought in registering opposition to the grooves of the stationary plates, constitute in such registering position 60 grooves of cylindrical shape or circular cross-section. To divide the lower steps of 65 the grooves parallel vertical ribs may be provided therein.

Further according to this invention a means may be provided for altering the size 70 of the crushed or disintegrated particles of the cereals. It is to be noted that the seeds to be crushed pass on their way downwards the several steps of the grooves of decreasing diameter, so that the size of the particles dropping from the apparatus is determined by the diameter of the lowermost step. Now the grinding members may be so disposed and arranged that either the stationary members or the reciprocating member or 75 members can be displaced and adjusted in vertical direction with relation to each other whereby the lowermost step or steps are rendered idle or inactive and a crushed material of correspondingly coarser quality is 80 obtained.

In order that the said invention may be clearly understood and readily carried 85 into effect, it will now be described more fully with reference to the accompanying drawings, in which:—

Figure 1 is a vertical longitudinal section of a disintegrating apparatus having but a single crushing element comprising three co-operating grinding plates.

Figure 2 is a plan view of the same and 90 Figure 3 is a sectional view taken on the line A—A of Figure 1.

It is to be understood that the drawings illustrate by way of example one embodiment of the invention only, to the details of 100 construction of which the invention is not limited, however, it being obvious that by employing any desired, preferably odd, member of grinding plates a machine of larger capacity and adapted for a power 105 drive may be obtained without thereby de-

parting from the gist of the present invention.

In the drawings only a small or household apparatus is shown having a single crushing element composed of three co-operating grinding plates and a handle for manual drive.

a is the casing and *b*, *c* are the two stationary rectangular plates made of steel or 10 cast-iron and having parallel grooves *f* on their inner faces, said grooves extending from the upper edge or top of the plates vertically downwards. The casing *a* is open at top and bottom, the flaring top opening *a*¹ 15 serving for the introduction of the seeds to be crushed and the bottom opening *a*² for the delivery of the crushed material.

The two grooved plates *b* and *c* are stationary within the casing, but they may be 20 removable therefrom and, if desired, adjustable in vertical direction with relation to the third plate *d* interposed between the two plates *b* and *c* to co-operate therewith. As hereinbefore stated, the displacement of 25 the two plates *b* and *c* affords a means for regulating the apparatus to obtain a product of finer or coarser quality just as desired of course, in lieu of the two plates *b* and *c* also the third plate *d* may be made to 30 be adjustable in vertical direction with relation to the plates *b* and *c* and the very same result will be achieved thereby.

The plate *d* is likewise of steel or cast-iron and has vertical grooves *f* on both sides 35 or faces to co-operate with the grooves of the two stationary plates respectively. To this end the plate *d* is elongated and the elongated ends *d*¹ and *d*² project from the casing through vertical slots *a*³ and *a*⁴ in the latter. The end *d*² of the plate *d* is provided with a slot *h* for the reception of a crank pin *g* on a suitably, journaled shaft *e*¹ having a driving crank *e*¹ and a handle *e*².

The co-operating faces of the three plates 45 *b*, *c* and *d* are grooved vertically as above stated, and the grooves *f*, preferably, have a semicircular cross-sectional area, so that when they coincide or register, which occurs twice at each reciprocation of the 50 driven plate *d*, they afford tubular or cylindrical receptacles for the seeds to be rough-ground. The grooves *f*, however, are not of the same size or diameter all throughout, but they are stepped and the successive 55 steps *f*¹, *f*² though of cylindrical contour, have a smaller diameter, so that the uppermost step has the largest size, say a diameter of about one half of an inch, and the lowermost step *f*² has the smallest diameter. The bottom ends of the grooves may 60 be subdivided by means of fine ribs *f*³ to obtain a further step of a still further reduced diameter.

In operation the seeds to be crushed are 65 introduced in the opening *a*¹ to enter the

uppermost step of the grooves *f* where they are, through the tearing or crushing action of the edges of the grooves due to the reciprocal movement of the plate *d*, disintegrated so far that they can enter the 70 next step *f*¹ of the grooves and so on until they drop from the lowermost step through the bottom opening *a*² in a finely disintegrated condition.

As hereinbefore stated, either the reciprocating plate *d* or the two stationary plates *b* and *c* may be arranged in a manner to allow of an adjustment in vertical direction for the purpose of rendering one or several steps of the grooves idle or inactive and 80 thereby obtaining a crushed product of correspondingly coarser quality, if desired.

As shown the two plates *b* and *c* are adjustable so that the lowermost step *f*³ or several lower steps can be put out of action 85 and the seeds having passed through the upper steps only, are delivered through the opening *a*² in a correspondingly coarser state. To this end the two plates *b* and *c* are mounted in the casing so as to be 90 slideable upwards in vertical direction, e. g., by means of a tongue and groove engagement. For shifting purposes the plates are provided with a semicircular extension having or affording a guiding means to co-operate 95 with a cam *i* of a shaft *k* duly supported in bearings provided in the wall of the casing *a*. The said shaft projects from the casing-wall and a crank with a handle *k*² is mounted on the projecting shaft end. By 100 rotating the said crank 180° the cam on the shaft is correspondingly turned with the result that both plates *b* and *c* are lifted to such an extent that the lowermost step or, as the case may be, several lower steps 105 of the reciprocating plate *d* are brought out of engagement with the corresponding steps of the lateral plates *b* and *c* and the crushed corn or other cereal drops through the delivery opening *a*² in a coarser condition 110 than if the disengaged step or steps of the crushing grooves had not been put out of action.

If it is desired to give the apparatus an arrangement whereby one or two or still 115 more steps can be put out of action at will, the cam or cams may be so shaped and arranged that the plates *b* and *c* can be lifted, stopped and fixed at different height corresponding to the different steps to be put 120 out of action. Thus by turning the crank handle 45° the lowermost step *f*³ in Figure 1 may be rendered inactive, at 90° the steps *f*³ and *f*² may be rendered idle, at 135° the steps *f*³, *f*² and *f*¹ may be put out of action. 125 In each case the crank or the shaft is to be secured in the position assumed after the partial rotation of the crank handle.

The mechanism for adjusting the plates for a desired coarseness of the seeds under 130

treatment may be simplified by dispensing with the semicircular extension and the guiding means and mounting the two plates *b* and *c* immediately upon lifting cams provided on the crank shaft.

Having now particularly described and ascertained the nature of this invention and in what manner the same is to be performed, what is claimed and desired to be secured by Letters Patent of the United States is:—

1. Apparatus for disintegrating corn and other cereals, comprising a casing, two stationary plates arranged edgewise in said casing and having vertical grooves of stepwise reduced diameters, a third plate intermediate between the said two plates and having vertical grooves of stepwise reduced diameters, means for adjusting the plates vertically relatively to one another, and a means for reciprocating the said third plate.

2. Apparatus for disintegrating corn and other cereals, comprising a casing, two stationary plates arranged edgewise in said casing and having vertical grooves of stepwise reduced diameters, a third plate located between the said two plates and having vertical grooves of stepwise reduced diameters, and ribs in the lowermost portion of said grooves for dividing said portion of the

3. Apparatus for disintegrating corn and other cereals comprising a casing, two stationary plates in said casing having vertical grooves of stepwise reduced diameters and a tongue and groove engagement with the casing for adjustment in vertical direction, a third plate disposed between the said two plates and having vertical grooves of stepwise reduced diameters, a cam shaft for lift-

ing the said two plates, and a means for reciprocating the said third plate.

4. Apparatus for disintegrating corn and other cereals, comprising a casing open at top and bottom, and having slots in opposite sides, two stationary plates arranged endwise in said casing and having vertical grooves of semicylindrical shape and of stepwise reduced diameters, a third plate disposed between the said two plates and having vertical grooves of semicylindrical shape and of stepwise reduced diameters, said third plate projecting through the slots of the casing and having a slot in one projecting end, means for adjusting the stationary plates vertically, and a means engaging in the slot of the third plate for giving the plate a reciprocatory movement.

5. Apparatus for disintegrating corn and other cereals, comprising a casing open at top and bottom and having slots in opposite sides, two stationary plates arranged edge-wise in said casing and having vertical grooves of semicylindrical shape and of stepwise reduced diameters, a third plate mounted between the two plates and having vertical grooves of semicylindrical shape and of stepwise reduced diameters, said third plate projecting through the slots of the casing, means for rendering the plates adjustable relatively to one another in vertical direction, and a means connected with one projecting end of the third plate for reciprocating the said third plate.
